UNITED STATES PATENT OFFICE.

FREDRICK VOGEL, OF NEW YORK, N. Y.

DESIGN FOR FRET-WORK FOR FURNITURE.

Specification forming part of Design No. **11,150**, dated April 8, 1879; application filed January 13, 1879.
[Term of patent 7 years.]

To all whom it may concern:

Be it known that I, FREDRICK VOGEL, of the city, county, and State of New York, have originated a Design of Fret-Work for Ornamentation of Furniture or other articles, of which the following is a full, clear, and exact description, reference being had to the accompanying drawing, forming part of this specification.

The fret-work consists of an upper part, A B C D, and a lower part, A' B' C' D', each part containing a series of triangular notches, a b c and a' b' c', with two equal sides, a b, b c, &c., the base-lines of the notches facing each other. Between any two adjacent notches the faces c a and c' a' remain, and globes g g are placed as distance-pieces between the respective faces c a and c' a'.

The sides a b, b c, a' b', b' c' of the notches are beveled off, as indicated by the lines m n' n o and m' n' n' o'.

The sides of the notches, instead of being straight, may be curved.

Round bars s s are placed between the angles of the notches in the upper and lower part. The bars are ornamented by beads t t.

Perforations p p may be placed between the notches.

What I claim as my invention is—

A design of fret-work for the backs of sofas, chairs, &c., the principal outlines of which consist of two straight faces, a c a c and a' c' a' c', broken by triangular recesses a b c a' b' c' at regular intervals, the recesses a b c a' b' c' of the two lines facing each other, as also do the straight parts a c and a' c', the straight parts being separated by globular distance-pieces g, and the re-entering angles of the triangular recesses being separated by round bars s, substantially as described.

FREDRICK VOGEL.
